UNITED STATES PATENT OFFICE.

JOHN HOLTZMAN, OF NEW YORK, N. Y., ASSIGNOR OF ONE-HALF TO BENJAMIN ROMAN, OF NEW YORK, N. Y.

RAZOR-BLADE-SHARPENING MACHINE.

Application filed March 3, 1922. Serial No. 540,872.

This invention relates to razor blade sharpening machines and particularly to the type that is utilized for sharpening double-edged flexible safety-razor blades, such as 5 are used in connection with the well known "Gillette" razors.

The invention herein is an improvement upon the machine shown and described in my previous application for Letters Patent, 10 filed May 27, 1921, Serial No. 473,052.

In the accompanying drawings,—

Fig. 1 shows a cross-sectional end elevation of the razor-blade sharpening machine.

Fig. 2 is a sectional side elevation of the 15 machine shown in Fig. 1.

Figs. 3 and 4 show details of the machine.

Figs. 5 and 6 show modifications of details of the machine.

Upon the axle 1, Figs. 1, 2, is fixed a 20 sharpening roll 2, which comprises a core 3 made preferably of wood, an exterior layer or rim 4 made of any suitable material or composition that affords an efficient sharpening, honing, or stropping surface, such as 25 rubber, leather, etc., and a mutilated or hollowed out portion 5. The axle 1 is rotatably mounted in bearings 6 of the casing 7 of the machine, whereby the roll 2 is free to rotate in any direction. A pinion 12 is 30 keyed upon the axle 1, a pinion 13 is mounted upon a stud 14 secured to the wall of the casing 7, a pair of similar gear-segments 15, 16 form part of a hub 15^a which is keyed 35 upon a rotatable drive-shaft 8 mounted in bearings 9 of casing 7, and said sectors are disposed oppositely to each other in the manner shown. To the shaft 8 is secured a 40 crank 10 and handle 11, whereby revolving of the crank in a clockwise direction, as viewed in the drawing, will freely rotate said drive-shaft 8 and segments 15, 16 accordingly. The segment 15 alternately meshes with and unmashes from the pinion 12, the segment 16 alternately meshes with 45 and unmashes from the pinion 13, and the pinion 13 is in constant mesh with the pinion 12. As the crank, therefore, is revolved, the segment 15, due to the ratios of their diameters, rotates the pinion 12 together with 50 the roll 2 a full revolution in a counter-clockwise direction. At the end of this revolution the segment 15 unmashes from the pinion 12, and the segment 16 then commences to mesh with the pinion 13 and there- 55 through transmits a reverse rotation to the

pinion 12, which then rotates together with the roll 2 a full revolution in a clockwise direction. As the revolving of the crank 10 is continued, this operation of the roll 2 is thus continuously repeated, viz, the roll performs 60 one anti-clockwise rotation and then backwardly a rotation in a clockwise direction, then again two similar reciprocating rotations, etc. The gear-segments 15, 16 are preferably spaced apart at 15^b in such manner whereby during the unmashing of the last tooth of the segment 15 from the pinion 12 the first tooth of the segment 16 commences its mesh with the pinion 13, which 65 action thus prevents free or ungeared rotation of the roll 2 during this change of transmission or direction of rotation.

Above the roll 2 is located a blade-holder 75 17, which is rotatably mounted in bearings 18, 19, of the casing 7. Said blade-holder comprises a shaft 20 the extremities 21, 22 of which are journaled in said bearings 18, 19 respectively, a cut-out flattened portion 23, and a bar 24 which is pivoted to the shaft 20 at 25 and has an extremity 26 which passes through and fits into a recess 27 formed in the shaft-journal 22. The double-edged flexible safety-razor blade 28, which is to be sharpened, is inserted into the blade-holder 17 and held thereby, by means of placing it upon the flat face 23, of shaft 20, with its openings 29, that are provided in the "Gillette" type blades, slipping over a pair of pins 30 projecting from the shaft-face 23, and then the bar 24 may be swung 80 about its pivot 25 to a position against the blade as shown. The bar 24 is securely locked in place by means of the cover 33 supplying a counter-part half-bearing for the shaft extremity 22; the said cover being 85 hinged at 33^a and locking securely to the casing at 33^b, by means of the spring-snap device 33^c. When the bar 24 is in locked position shown, the pins 30 pass into recesses 90 34 formed therein. To remove the blade 95 28 from its holder 17 it merely requires opening and swinging back of the cover 33 to release the bar-extremity 26 and then swinging the bar 24 upwardly about its pivot 25. 100 Upon the sector-shaft 8 is keyed a gear 53 which meshes with a similar gear 54 rotatable loosely upon the roll-axle 1, and to the gear 54 is secured a disk 40, provided with a gear-segment 41, which disk is also rotatable loosely upon the axle 1, whereby for 105 110

each revolution of the gear-segments 15, 16 or each two reciprocating rotations of the roll 2 a single revolution in an anti-clockwise direction is imparted to the sector 41. Upon the blade-holder shaft 20 is keyed a gear 35, which meshes with the segment 41, and as the ratio of the latter to the gear 35 is that of one-half to one, the gear 35, blade-holder 17, and blade 28 receive half a revolution in a clockwise direction for each two reciprocating rotations of the roll 2 and each revolution of the segment 41 and crank 10. A pair of oppositely disposed arms 36 are keyed upon the shaft 20 adjacent to the gear 35. Upon the axle 1 is keyed a disk-cam 39 having a mutilated portion 39^a, in alignment with the mutilated portion 5 of the roll 2.

A spring 57, Figs. 3, 4, is secured to a lug 58 forming part of the casing 7, and the terminals of said spring bear against flattened portions 59 of the blade-holder shaft 20, whereby said spring normally tends to dispose the blade-holder so that the blade 28 is radial to the axle 1 and within the mutilated portion 5 of the roll, when said portion 5 is opposite to the blade, as shown in Figs. 1, 2. As the roll 2 performs its anti-clockwise rotation, and assuming that the gear-segment 41 has just meshed with the gear 35, as shown in Fig. 1, and thus positioned the blade 28 with its edge 46 downwardly, the roll-shoulder 42 which is suitably configurated, strikes the blade 28 and flexes it, contrary to the disposition thereof by the spring 57, thereby causing its edge 46 to land upon the roll and to exert pressure of its edge-side 47 against its periphery so that as the roll rotates it effectively sharpens this edge-side. During this sharpening operation the blade 28 is maintained fixed, in the operative position, by means of the arm 36 bearing against the periphery of the rotating disk-cam 39. When the arm 36 is thus in engagement with the disk-cam 39 and is retained by the latter in the operative position, it maintains the blade 28 at a requisite inclination or angularity relatively to the periphery of the roll 2, which permits proper flexure thereof and disposition of its edge-side 47 at a proper tangency to the roll 2, for executing efficient sharpening thereof. When the blade 28 is in the angular sharpening position and against the roll the spring 57 tends to partially rotate the blade-holder and swing the blade radially to the axle 1. Upon completion of the first anti-clockwise rotation of the roll 2, therefore, the spring 57 restores the blade-holder 17, blade 28, and arms 36 to their previous positions with the blade-edge 46 disposed within the mutilation 5 of the roll. The roll 2 now performs its second and révèré or clockwise rotation, and causes the same blade-end to be flexed oppositely and

the opposite arm 36 to engage the cam 39 for retention of the blade in proper sharpening state, in the above described manner, thereby subjecting its adjacent edge-side 48 to operative sharpening pressure against the roll-periphery, so that, as the roll performs this rotation it effectively sharpens this edge-side. In the swinging of the blade 28 it is not obstructed by the roll 2, due to its passing through its mutilated portion 5, and the arm 36 is not obstructed by the cam 39, due to its mutilated portion 39^a. At the completion of the second revolution of the roll 2, the gear-segment 41 meshes with the gear 35 and thereby imparts half a revolution to the blade-holder 17, the arms 36, and the blade 28, which action thus directs the blade-edge 43 into the mutilation 5 of the roll 2. As the roll 2 now performs its third rotation in an anti-clockwise direction, it strikes the blade, flexes it, and sharpens its edge-side 44. At the completion of the third revolution of the roll 2 the blade-edge 43 is still directed into the mutilation 5 by the spring 57 and the fourth edge-side 45 is brought to bear against the roll-periphery, and as the roll performs its fourth revolution in the clockwise direction it accordingly sharpens this edge-side effectively.

If desired the terminals of the arms 36 may be provided with rollers 56, as shown in Fig. 5, which will tend additionally to reduce the friction between these two elements. Should it be desired to sharpen double-edged rigid or non-flexible blades, a crescent-shaped spring 62 may be secured to the terminals of the arms 36, as shown in Fig. 6, which will cause these springs to intervene between the arms and the cam 39. In this manner resiliency will be imparted to the arm 36 while it bears against the said cam, and the rigid blade will thereby bear resiliently against the roll 2, which resilient pressure of the blade against the roll is essential in the sharpening of rigid blades.

As the gear ratios of the segments 15, 16 to that of the pinions 12, 13 is that of two to one, it will be evident that for each two revolutions imparted to the operating crank 10, the roll 2 will automatically sharpen each of the edge-sides 47, 48, 44, 45 of the blade 28 individually and successively, and as the revolving of the crank is continued the sharpening of all the four sides of the two edges of the blade is continuously repeated until the razor-blade becomes completely and efficiently sharpened. When the sharpening of the razor-blade is completed, the same may be readily removed from the machine and another blade may be inserted in the holder 17, and a similar sharpening operation may be performed thereupon. It will be evident that any other type of blade-holder may be here utilized in place of the blade-holder 17.

Variations may be resorted to within the scope of the invention, and portions of the improvements may be used without others.

Having thus described my invention, I claim:

1. A sharpening machine for double-edged razor-blades having the combination of a rotatable sharpening roll, a rotatable blade-holder, mechanism for driving said roll and holder, said holder having an element adapted to lock the blade thereto, a casing for the machine, a cover for said casing, and means to lock said element in operative state by the closing of said cover.
2. A sharpening machine for razor-blades having the combination of a rotatable sharpening roll, a drive shaft, mechanism to rotate said roll alternately in opposite directions while said shaft is driven in one direction, a pivoted blade-holder, means to reverse said blade-holder, means to retain said holder to maintain the blade in operative sharpening relation to said roll, and means to maintain said retaining means in operative state during the sharpening operation.
3. A sharpening machine for double-edged razor-blades having the combination of a rotatable sharpening roll, a drive shaft, mechanism to rotate said roll alternately in opposite directions while said shaft is driven in one direction, a pivoted blade-holder, means to reverse said blade-holder, an arm extending from said holder to retain the latter in sharpening relation to said roll, and a rotatable member bearing against said arm to retain it in operative position during the sharpening of the blade.
4. A stropping machine for double-edged razor blades comprising a stropping element, a blade-holder, an arm secured to said blade-holder, a member, said arm riding on said member and keeping the blade in tension against the stropping element, an operating handle, and means actuated by said handle to dispose all four edge-sides of the blade to said stropping element individually and successively.
5. A stropping machine for double-edged razor-blades comprising a stropping element, a blade-holder, an arm secured to said blade-holder, a member, said arm riding on said member and keeping the blade in tension against the stropping element, means to render said tension yieldable, an operating handle, and means actuated by said handle to dispose all four edge-sides of the blade to said stropping element individually and successively.
6. A sharpening machine for double-edged razor blades having the combination of a rotatable sharpening roll, a rotatable blade-holder, means for rotating said roll alternately in opposite directions, and means for rotating said blade-holder in one direction only.
7. A sharpening machine for double-edged razor blades having the combination of a rotatable sharpening roll, a drive-shaft, mechanism for rotating said roll alternately in opposite directions while said shaft is revolved in one direction, a rotatable blade-holder, and means driven by said shaft for rotating said blade-holder in one direction only.

Signed at the city of New York, in the county of New York, and State of New York, this 2nd day of March, A. D. 1922.

JOHN HOLTZMAN.
